UNITED STATES PATENT OFFICE.

JOHN J. SMITH AND FRED O. CASSIDY, OF OWEGO, NEW YORK.

IRONING-BOARD STANDARD.

1,171,754.

Specification of Letters Patent. Patented Feb. 15, 1916.

Application filed July 7, 1915. Serial No. 38,557.

To all whom it may concern:

Be it known that we, JOHN J. SMITH and FRED O. CASSIDY, citizens of the United States, residing at Owego, in the county of 5 Tioga and State of New York, have invented certain new and useful Improvements in Ironing-Board Standards, of which the following is a specification.

Our invention relates to an improvement 10 in ironing board standards in which a collapsible leg standard is provided with means for firmly and removably mounting an ironing board thereon and it has for its object to provide a light, firm and braced leg support 15 port and on which an ironing board may be removably mounted and which leg support can be readily folded up and clamped in the folded form.

With this object in view our invention 20 consists in certain novel features of construction and arrangement of parts as will be hereinafter fully and more particularly described and pointed out in the claims, reference being had to the accompanying drawings in which—

Figure 1 is a side elevation of our device, with ironing board mounted upon the same. Fig. 2 is a side view of a fragmentary part 30 of our device. Fig. 3 is an end elevation of our device without the ironing board. Fig. 4 is an interior end elevation of a fragmentary part of our device. Fig. 5 is a plan view of our standard. Fig. 6 is a plan view of our device folded up without the ironing 35 board. Fig. 7 is a side view of our device folded up without the ironing board. Fig. 8 is a plan view of the underside of the ironing board. Fig. 9 is an end view of the narrow end of the ironing board partly in 40 cross section.

Similar letters refer to similar parts throughout the drawings.

In our device we have the end standards A and A' composed of the legs 2, 2 and 2'. 45 2'; the cross braces 3 and 3' and the top braces 4 and 4'; also the inner braces 5 and 5', 6 and 6'. In the top of the end standard A' we have mounted the pin 9. Mounted between the lower braces 3 and 3' of the end 50 standards A and A' we have the cross brace B composed of two strips of material 10 and 10' bolted together by means of the bolts or screws 11, 11 and forming between the strips 10 and 10' the slot 12 and between 55 the two strips 10 and 10' we have mounted the turn screws α , α which turn screws pass

through the ends of the slot 12 and thus permitting the sides of the slot to be drawn together in tension: Pivotally mounted in the end braces 5 and 6 and 5' and 6' we have the wire bails 13 and 13' which wire bails 13 and 13' pass through the slot 12 and are slidably mounted therein. On the upper side of the cross brace B we have mounted the turn button 14; between the 60 ends of the diagonal braces 5 and 6 we have the opening 15. On the top of the cross braces 4 and 4' of the standards A and A' we mount our ironing board C which board C has on its under side the cleats 16, 16 and 70 16 on the under side at one end we have the recess 17 adapted to receive the pin 9. At the other end of ironing board C we have the wire ring or hook projection 18 or lug of any similar formation which when the 75 ironing board is mounted in place is adapted to enter and rest in the opening 15 between the ends of the diagonal braces 5 and 6 as shown in Fig. 5. Mounted on the top of the brace B we have the hinges 19, 19 80 which are also mounted upon the cross braces 3 and 3' thus giving the cross brace B hinged connection with the cross braces 3 and 3' of the standards A and A'.

When we desire to fold our device up we remove the ironing board C. We then loosen the thumb screws α , α which allows free play of the bails 13 and 13' to slide in the slot 12 and we then bend toward each other the hinged 85 end standards A and A' and by so doing the 90 sliding bails 13 and 13' pass each other in the slot 12 until they assume the position as shown in Fig. 6 and until the end braces are lowered to a horizontal position such as is shown in Fig. 7 and the pin 9 in the cross 95 brace 4' enters the opening 15 in the top of the cross brace 4. We then when in this position, turn the turn button 14; the flanges of which extend out over the diagonal braces 5 and 6 in standard A and thus hold the 100 standards in this horizontal position firmly.

When we wish to unfold and set up our standard we loosen the turn button 14 until the flanges are removed from the diagonal braces 5 and 6 and then we raise the hinged 105 standard A and the hinged standard A' to a vertical position and by so doing cause the bails 13 and 13' to slide backward in the slot 12 until they reach the extension recesses of the slot 12, 12' each respectively; 110 the one recess being on a line with the lower side of slot 12 and the other recess on a line

with the upper side of slot 12. We then screw down the turn buttons α , α which causes the sides of the slot extensions 12' and 12' to be drawn together and firmly gripping said bails 13 and 13' and the standards A and A' are thus held in a firm, vertical position ready to receive the ironing board C.

Having thus described our invention, what we claim as new and for which we desire Letters Patent is as follows:

1. In ironing board standards leg frames consisting of two parallel frames each composed of two legs joined together by an upper and lower cross bar; two diagonal braces connecting between the upper and lower cross bar; a bail hinged to said diagonal braces; a connecting bar each end of which is hinged to the lower cross bar of the opposite leg frame, said bar being composed of two parallel strips; a slot projecting between the strips; the slot having an upper extension at one end and a lower extension at the other end; said bails being slidably mounted within said slot; a button mounted on the upper surface of the connecting bar; a turn screw mounted in the parallel strips at each end of connecting bar between the slot and the end of bar; a pin mounted in upper cross bar of one leg frame; a recess in upper cross bar of opposite leg frame; an

ironing board having an opening on under side in one end and adapted to receive the pin of upper cross bar of leg frame and a pin mounted on underside of other end adapted to enter the recess in opposite leg frame, all for the purposes specified.

2. In an ironing board support, leg frames, each composed of two leg members connected together by upper and lower cross-bars, a connecting bar hingedly secured to the lower crossbars of each leg frame said bar being provided with a longitudinal slot intermediate its ends, supporting bails pivotally secured to the leg frames and adapted to traverse the slot in the connecting bar when the leg frames are folded upon said connecting bar, means to narrow the slot in the connecting bar to bind upon the bails when the leg members are in vertical position whereby the leg bars are braced and means carried by the connecting bar for securing the leg frames in position when said frames are folded upon said connecting bar.

In testimony whereof we have affixed our signatures in presence of two witnesses.

JOHN J. SMITH.
FRED O. CASSIDY.
